UNITED STATES PATENT OFFICE.

EDWARD D. SCHMITT, OF BROOKLYN, NEW YORK, ASSIGNOR TO MONARCH SEAL COMPANY,
OF NEW YORK, N. Y., A CORPORATION OF NEW YORK.

SEALING-HEAD FOR BOTTLE-SEALING MACHINES.

No. 880,490.

Specification of Letters Patent.

Patented Feb. 25, 1908.

Application filed July 16, 1907. Serial No. 384,093.

To all whom it may concern:

Be it known that I, EDWARD D. SCHMITT, a citizen of the United States, residing at Brooklyn, in the county of Kings and State 5 of New York, have invented certain new and useful Improvements in Sealing-Heads for Bottle-Sealing Machines, of which the following is a specification.

This invention relates to sealing heads for 10 bottle sealing machines.

The invention contemplates a sealing head adapted for applying a hard metal flanged cap to a bottle having an annular head or locking shoulder adjacent to its mouth, and 15 locking said cap by indenting its flange at intervals.

It will be understood that the head is commonly used in conjunction with a suitable bottle support, which support is moved 20 toward the head or the head moved toward the support to get the required sealing pressure. The movements of these parts may be brought about in any well known or suitable way, and as this invention does not reside 25 in a mechanism for moving these parts, but in the head itself, only the head is shown, which will be sufficient to enable those skilled in the art to understand the construction and operation.

30 In the drawings: Figure 1 is a central vertical sectional view of a head constructed in accordance with my invention, showing a bottle cap in dotted lines in the seal holding cavity of the plunger; Fig. 2 is a similar view 35 of the lower part of a head, showing the upper part of a bottle within the seal cavity, with the parts in about the position they assume in locking the flange of the seal; Fig. 3 is a detail perspective view of one of the 40 devices for projecting the locking pins into the seal holding cavity to lock the seal; Fig. 4 is a similar view of one of the slidable locking pins, and Fig. 5 is a plan view of the 45 plunger showing the manner of recessing its outer face or periphery to receive an extension of the pin operating devices, the plunger being partly broken away to show one of the seal holding pins.

50 Referring to the drawings, the numeral 1 designates the head, comprising in the main the upper part 2 and the lower section 3. The part 2 is internally threaded as indicated at 3' for the reception of the threads of a screw cap 4, and the lower part of the part 2 55 is externally threaded as indicated at 5 to

receive the threads of the lower part 3, whereby the upper and lower parts are separately connected, which arrangement makes it easy to reach the interior of the head to repair the inside mechanism, or in assembling the parts at the outset.

The lower part 3 of the head casing has integral therewith a plurality, preferably six, of radially arranged barrels, 5' each having a bore 6 therein, for the reception of the devices which operate upon the slidable pins carried by the plunger. The description of one of these devices will serve as a description for the rest, as said devices are identical in construction. These devices consist of a circular head 7 to which is connected a shank 8, squared at its outer end as indicated at 9. The squared portion passes through a squared opening 10 in a nut 11, which construction prevents the devices from turning.

Interposed between the head 7 and the end 75 11 is a spiral spring 12, tending at all times to keep the device projected toward the plunger. Each head 7 is provided with a narrow extension 13 having a bevel or cam surface 14 at its lower end. These extensions 13, when the parts are assembled, extend into and ride in vertical grooves 15 in the outer 80 face of the plunger 16. The plunger is provided with a number of radially arranged recesses 17, which contains sliding pins 18, having cam surfaces 19 on their outer ends and reduced inner ends 20, terminating in indenting points 21 which, in the operation of the 85 head, engage and indent the flange of the seal 90 into locking engagement with the locking shoulder on the bottle. Each pin is provided on its upper side with a groove 22, which receives and embraces the lower portion of a screw or threaded key 23, one of 95 which is put into the plunger above each pin. The recesses 17 are reduced at their inner 100 ends and open into the seal holding cavity 24 of the plunger. The plunger is reduced in diameter at its upper end as indicated at 25 and extends a proper distance into the upper 105 part of the head casing, where its upper end bears upon the end wall of the cap 4. The downward movement of the plunger is limited by a ledge 27 formed on the lower head portion upon which ledge the plunger normally rests, as shown in Fig. 1.

The seal may be temporarily held in the seal holding cavity by any suitable means, but I preferably employ spring-backed pins 110

with their ends projected slightly within the cavity, such as are shown and described in my application Number 373,076, filed May 11, 1907.

5. In operation, when a bottle is in position to be sealed and the head moved down or the bottle moved up as the case may be, the sealing spring will be compressed, permitting the plunger to yield upwardly until the cam surfaces 14 on the pin operating devices engage the cam surfaces 19 of the pins 18, when the pins will be yieldingly forced inward, projecting their inner ends into the seal holding cavity where they indent the flange of the seal into locking engagement with the bottle. The pin operating devices operate yieldingly on the pins, by reason of the springs 12, thus eliminating the possibility of crushing or breaking a bottle. During this movement, 10 the extensions 13 of the head 7 of the pin operating devices ride in the grooves 15 in the periphery of the plunger. The indenting ends of the pins 18 are so shaped that the removal of the bottle from the head after it has 15 been sealed, will force them back in their recesses in the plunger to position to be again operated upon by the pin operating devices in the further operations of the machine. The screws 23 keep the pins 18 from turning 20 in their recesses, and insure the proper engagement between the cam surfaces 19 of the pins and the cam surfaces on the extensions 25 of the pin operating devices.

Claims.

35. 1. In a head for bottle sealing machines, a yielding seal applying plunger having a plurality of substantially radially arranged recesses therein, a slideable pin in each recess formed with a seal indenting point at its forward end and a cam surface at its rear end, a plurality of laterally yielding devices independent of the plunger, each device having a cam surface in the path of movement of the rear ends of the seal locking devices, where- 40 by, when the plunger is moved upward, the seal locking devices will be simultaneously projected forward to bring their seal indent-

ing points into engagement with the flange of a seal to lock the same at intervals upon the locking shoulder of a bottle.

2. In a head for bottle sealing machines, a yielding seal applying plunger having a plurality of substantially radially arranged recesses therein, a slideable pin in each recess formed with a seal indenting point at its forward end, and a cam surface at its rear end, a plurality of laterally yielding devices carried by the head casing, each device having a cam surface in the path of movement of the rear ends of the seal locking devices, whereby when the plunger is moved upward, the seal locking devices will be simultaneously projected forward to bring their seal indenting points into engagement with the flange of a seal to lock the same at intervals upon the locking shoulder of a bottle.

3. In a head for bottle sealing machines, a yielding seal applying plunger formed with a seal holding cavity and a plurality of substantially radially arranged recesses therein, and a vertical groove opposite each radial recess, a seal locking device in each radial recess formed with an indenting point on its forward end and a cam surface on its rear end, the cam surfaces on the rear ends of said locking devices extending into the vertical grooves in the plunger, a plurality of laterally movable spring backed pins mounted in the head casing, one for each locking device, each pin having a cam portion extending into the vertical grooves of the plunger in the path of movement of the cam ends of the locking devices, whereby when the plunger is moved upward, the locking devices are simultaneously projected forward into engagement with the flange of a seal to indent it at intervals into locking engagement with the locking shoulder of a bottle.

In testimony whereof I affix my signature in presence of two witnesses.

EDWARD D. SCHMITT.
